SEWING MACHINE

Solomon Adler, Kew Gardens, N.Y., assignor to Nippon Sewing Machine Mfg. Co., Ltd., Nagoya, Japan, a corporation of Japan

Filed Oct. 1, 1959, Ser. No. 843,852
9 Claims. (Cl. 112—158)

This invention relates to a structurally and functionally improved sewing machine by means of which ornamental and novel stitch patterns may be produced by relatively unskilled operators.

It is a primary object of this invention to furnish such a machine involving a novel and simple mechanism capable of ready and speedy production and which will operate over long periods of time with freedom from all difficulties.

Among further objects of the invention are the combining of a mechanism of this type with the needle bar of a sewing machine in order to impart predetermined movements to the latter such that a zigzag stitch will be produced, and the combining of that mechanism with the feed dog control of the machine so that a great variety of ornamental stitches will be available to the user of the mechanism.

With these and other objects in mind, reference is had to the attached sheets of the drawings illustrating practical embodiments of the invention and in which:

FIG. 1 is a fragmentary perspective view of a preferred form of control mechanism;

FIG. 2 is a sectional front view of that mechanism;

FIG. 3 is a perspective view of a pair of components included within the assembly as shown in FIGS. 1 and 2;

FIG. 4 is a perspective view of the mechanism which may be present in a sewing machine with the present teachings incorporated therein; and

FIG. 5 is a view similar to FIG. 1 but showing an alternative form of mechanism.

Referring primarily to FIG. 4, by way of illustration of a sewing machine to which the present invention may be applied, the dot-and-dash lines under the numeral 10 indicate a suitable machine bed from which a column or pedestal extends in an upward direction and is continued in the form of an arm 12 terminating in a head 13. In accordance with conventional practice, there extends through the upper ends of the head and pedestal portions and throughout the length of the arm a rotatably mounted shaft 14. At one end, this shaft conveniently has associated with it a wheel 15. Shaft 14 is rotated by an electric motor or otherwise, and may be driven by a belt (not shown) engaging the pulley portion 16 of wheel 15. Adjacent its opposite end, shaft 14 conveniently mounts a crank 17 which by means of a pitman or link 18 serves to reciprocate a needle bar 19. The latter is slidably mounted within a guide 20 pivotally supported as at 21 so that the needle bar in addition to straight reciprocation may move laterally.

Within the bed 10 of the machine, rock shafts 22 and 23 are rotatably supported. Shaft 23, by means of a crank 24, serves to reciprocate feed bar 25. The latter is guided in any desired conventional manner and connected to a feed dog 26. Shaft 22 by means of gearing 27 serves to drive a gear 28 fixed to a loop lifter 29 to actuate the latter. Also it moves the feed dog in accordance with usual practice. Shafts 22 and 23 are oscillated conveniently by rocking cranks 30 and 31 and connected respectively to pitmans 32 and 33. The former has its upper end coupled to a crank portion 34

2

forming a part of drive shaft 14. Pitman 33 is oscillated by means of an eccentric 35 carried by shaft 14 and conveniently engages that eccentric by being provided with a forked upper portion 36 between the arms of which the eccentric rides. Pitman 33 is pivotally supported as at 37 by a suitable portion of the housing.

The head 13 of the machine in a conventional manner carries a spring-influenced presser bar 38 supporting at its lower end a presser foot 39 which lies adjacent feed dog 26 and the needle carried by bar 19. Beyond this, the mechanism may include a lever 40 extending outwardly from the housing of the machine and by means of which, in well-known manner, the stitch length and the direction of the feed of the material, as controlled by the dog 26, are regulated. Also, there may extend beyond the housing of the machine a control or knob 41, in addition to a pattern knob or control 42. The former serves to permit regulation of the bight. The latter controls the stitch pattern as produced by the machine in accordance with the present teachings.

In FIG. 4 various detailed structures have been omitted. All of them may be more or less conventional and are well understood by those conversant with the art and the structures necessary in a sewing machine of the zigzag type. They will include proper bearings for shaft 14 and suitable couplings between these bearings and the housing portions of the machine. Similar necessary coupling structures will exist between the supports for shafts 22 and 23 and the bed portion of the machine as well as between the pivot 21 and the head 13. Other structures have been shown but need not be herein described, in that their design and operation are well understood, not alone in the case of straight stitch, but also in the instance of zigzag machines.

The lateral movements of needle bar 19 are controlled by means of a link 43. This link has one of its ends pivotally connected as at 44 to the support or carriage 20. It is apparent that as this link is reciprocated, support 20 will rock around pivot 21 to thus cause needle bar 19 to oscillate.

With a view to reciprocating link 43, drive shaft 14 mounts a gear 45. The latter meshes with the teeth of a gear 46 connected by a suitably supported shaft with an eccentric 47. As in FIG. 1, a member 48 having its inner face channeled receives within that channel the eccentric. That member is rockingly supported as at 49 and carries in a channel defined by flanges 50 a block 51, so that the latter may slide toward and away from the pivot 49. That block is connected to the inner end of link 43. It is apparent that as shaft 14 rotates, needle bar 19 will be reciprocated. Also, member 48 will oscillate around its pivotal mounting 49 incident to the action of eccentric 47. With such oscillation, link 43 will reciprocate to impart lateral movement to carriage or guide 20 and consequently the needle carried by bar 19. The farther block 51 is shifted away from pivot 49, the greater will be the amplitude of reciprocation imparted to link 43. The more block 51 is moved towards pivot 49, the smaller will be the amount of reciprocation. With the inner end of link 43 in substantial alignment with pivot 49, no reciprocation will occur.

As in FIG. 1, wherein the mechanism is achieving merely lateral movements of the needle bar, the pattern dial or control 42 is secured to a shaft 52 supported for rotation within the housing. As illustrated, that dial conveniently carries indicia in the form of a series of symbols representative of the type of stitch which will be produced according to the position assumed by the

dial. There may also be included in these symbols an indication of a position assumed by the parts in which no mechanism will automatically function to produce fancy or embroidery stitches. A registering mark or equivalent, as indicated, may serve as a guide with which the various subdivisions of the dial may be aligned. Secured to shaft 52 are a plurality of elements 53 having cam or actuating portions 54. As hereinafter brought out, these may serve as selectors under the control of the operator to permit control of the machine so that a desired stitch will be produced.

To achieve this, a supporting shaft 55 is provided adjacent and parallel to shaft 52. This shaft mounts a plurality of arms 56 each in permanent alignment with one of the elements 53. The inner ends of arms 56 terminate in follower portions 57 engageable with the cam or projecting parts 54. The opposite ends of arms 56 serve to support operating cams. The design providing for this structure is best illustrated in FIG. 3.

In that view, the numeral 58 designates an aperture within an arm 56 and through which shaft 55 extends so as to rockingly support the arm. Opposite the follower portion 57 the arm provides in its end zone an opening 59. A cam 60 embodies a suitable configuration and has extending from it a disk-shaped portion 61 of a diameter related to the diameter of opening 59. This disk portion may be either integral with the cam or else suitably affixed to the same. Its thickness should preferably be equal to that of arm 56. As will be apparent, with disk portion 61 within the aperture 59, the cam will be supported for rotation by the arm 56. Also, the weight of the assembly thus furnished will assure that the arm 56 under the action of gravity will tend to maintain its follower portion 57 in an elevated position. Cam 60 is rotated with respect to the arm preferably by forming in the inner edge of the disk 61 an annular series of gear teeth 62, thus furnishing a ring gear.

In common with elements 53, the cam and arm assemblies 56-60 are disposed adjacent each other. A shaft 63 is supported for rotation by the arm portion 12 of the housing and extends through the openings defined by the ring gears 62 of the several cams. Within that area, this shaft is formed with teeth 64 to provide a pinion portion common to and meshing with all of the ring gears of the several cams. A worm 65 is mounted by drive shaft 14 and engages with a worm wheel 66 fixed against movement with respect to shaft 63. Accordingly, as shaft 14 rotates, shaft 63 will be turned, and due to the fact that its pinion portion drivingly engages the teeth of the cam elements, the latter will be constantly rotated.

Considering FIG. 2 in conjunction with FIG. 1, it will be observed that a fine transverse shaft 67 is rotatably supported by the housing and that a follower 68, preferably in the form of a rod, is provided which overlies the entire bank of cam assemblies driven by rotation of shaft 63. This rod is mounted by arms 69 carried by shaft 67. The follower thus provided is urged in the direction of the cam peripheries by securing an arm 70 against movement with respect to shaft 67 and connecting to that arm one end of a spring 71, the opposite end of which is secured to a part fixed with respect to the housing. By this structure it is obvious that the follower shifts toward and away from the axis of shaft 63 and is not capable of moving axially of that shaft or shaft 67. The cams 60 being maintained against sidewise movements with respect to arms 56 and the latter being maintained by their coupling with shaft 55 against axial movements with respect to that shaft, it is apparent that these cams will maintain fixed stations as they are rotated by the turning of shaft 63.

With a view to having the movements of link 43 respond to the driving forces exerted not alone by eccentric 47 but also by the operating cams, a coupling structure is employed. That structure conveniently includes an arm 72 affixed to shaft 67 and carrying a pin 73. This pin

rides within a notch 74 formed in a bell crank member 75. The latter is pivotally supported with respect to the housing of the machine by a shaft indicated at 76. The second arm of bell crank lever 75 also conveniently terminates in a notch portion 77. Riding within the latter is a pin 78 affixed to the inner end of link 43. It is thus apparent that as follower 68 is shifted by a given cam 60 of the group or series carried by arms 56, shaft 67 will be rocked to correspondingly move arm 72. This in turn will transmit rocking motion to bell crank lever 75 and thus the pin 78 affixed to link 43. This will cause the inner end of the link to be moved towards and away from the pivot 49. As illustrated, shaft 67 may have affixed to it a knob 79 positioned beyond the exterior face of the housing. A detent structure (not shown) may serve to retain shaft 67 in a position where follower 68 is by knob 79 above the cams so that the follower is not effected by them.

Considering the operation of the mechanism so far described, it is apparent that with the machine properly threaded and material disposed below the presser foot 39, a rotation of shaft 14 will cause needle bar 19 to be reciprocated and the feed dog 26 to shift the material in the intervals between stitches. Simultaneously with the formation of these stitches, link 43 may be reciprocated due to the oscillation of member 48 around its pivot 49 as caused by the eccentric 47. If desired, a structure may be furnished for preventing this reciprocation by simply attaching to the shaft 80, mounting knob 41, an eccentric 81 which will bear against the edge of link 43; a spring 82, conveniently associated with the outer arm of bell crank 75, assuring this contact. Obviously, if eccentric 81 is shifted to a position such that link 43 has its inner end lowered to a point where pin 32 is substantially in line with pivot 49, no movement of link 43 will occur, and straight stitching will result. Under these or other circumstances, control 40 may be actuated to govern the operation of rock shaft 22 to vary the length of the stitches or to cause a reverse feeding of the material being operated on.

Assuming that eccentric 81 does not occupy a position such that link 43 is maintained in stationary condition, and that dial 42 has been shifted to a position at which the portion 54 of a desired selector element 53 is in engagement with the follower 57 of an arm 56, then the opposite end of that arm will be elevated. With such elevation, the corresponding cam will be raised to the zone of follower 68. Such raising will not result in a disengagement of teeth 64 from the teeth 62 of the selected cam or any other cam of the group. Consequently, the relationship of the several cams will be maintained. With the establishment of the described condition of the parts, then selected cams 60 will individually rock follower 68. This movement will be transmitted by shaft 67 to crank 72 and thus to the inner end of link 43, which will be shifted toward and away from pivot 49.

Accordingly, instead of that link being simply reciprocated merely in a manner corresponding to the contours of eccentric 47, a modulation and variation of such shifting will occur as determined, by the cam and rest portions of operating unit 60 as superimposed upon the actions and movements created by eccentric 47. Thus, a desired stitch pattern is produced. As will be appreciated, by manual adjustment of knob 41, the characteristics of this pattern may be altered. In other words, by shifting the inner end of link 43 upwardly, away from the pivot 49, that link will still receive the combined impulses and movements transmitted to it by eccentric 47 and the cam 60 which has been selected, but the pattern will have a broader scope. Conversely, by moving the link towards pivot 49, the scope of the pattern will be diminished as that link moves downwardly under the influence of spring 82 or otherwise.

The arrangement of apparatus may be modified so

that the lateral movements of the needle bar are governed by three controls, in addition to any control exercised by actuation of knob 41 or its equivalent. These three controls will involve the cam or eccentric 47 and a grouping of mechanism such as is shown in FIG. 1 to modify and amplify the resultant movements of link 43 as afore described. In addition, a substantial duplication of the mechanism as generally shown in FIG. 1 will be present. This duplication will control the position of the needle, in other words, the definite shifting and maintaining of the needle bar for desired time intervals in positions at which the needle will stitch along a given line or else to the left or right of that line. Such an arrangement of mechanism has been shown in FIG. 5.

In that view, the numeral 42 again indicates a pattern dial. This dial is secured against movement with respect to a shaft 83 corresponding to shaft 53 as previously described. In common with the previous illustration, this shaft mounts a group of lifter selector cams in the form of elements 84, each formed with projections 85. These will cooperate with pattern cam lifters embracing arms 86 mounted solely for rotation with respect to a shaft 87'. The latter corresponds to shaft 55 as previously described. These arms will also have follower portions to cooperate with the projections 85 of elements 84 and will mount cams 87 corresponding to the cams 60; one of those cams 87 being shiftable to an elevated position to cooperate with a follower bar 88 mounted to oscillate shaft 89. That shaft will also carry a crank 90 operatively coupled to a bell crank 91 in turn connected to link 43 in the same manner as described in connection with FIG. 1. It will be observed that shaft 89 does not extend across the entire housing. Rather, in FIG. 5, this shaft terminates substantially midway of that housing. In line with that shaft is a second shaft 91" which by means of crank 92 mounts a follower 93 common to a group of cams 94. Those cams correspond to and are preferably of the same general type as cams 87 and the cams 60 as illustrated in FIG. 3. Also, they are mounted on arms 95 corresponding to the cam lifter arms 86 and 56. Arms 95 are mounted on shaft 87' and have follower portions 96 engageable with projections 97 forming parts of each of a group of selector elements 98. Those elements function as lifter selector cams in the same manner as elements 84 and 53. At this time it is to be noted that in FIG. 5 merely four elements, arms and control cams have been shown in each of the two groups illustrated. This has been done with a view to avoiding confusing complications of the drawings. As will be understood, a greater or lesser number of control cams, together with the necessary associated mechanism, might be included in each group; the same being true of the structure hereinafter described in connection with FIG. 4.

In any event, shaft 91' has connected to it an arm 99. This arm, by means of a pin and slot connection 100, serves to rock a bell crank lever 101 around its point of pivotal mounting 102 as shaft 91 oscillates. The second arm of the bell crank lever is connected conveniently by a pin and slot connection 103 with an arm 104. The latter is secured to a shaft corresponding precisely to shaft 67. This shaft carries an arm or crank 105 to which a member 48 is pivotally connected as at 106. This connection is provided in lieu of the pivot 49 in FIG. 1. Also, in common with the previously described structure, the main drive shaft 14, by means of suitable gearing 45 and 46, serves to rotate the eccentric or cam 47 controlling the movements of member 48; a block 51 being slidably confined for movement longitudinally of member 48 and serving by means of a pin 32 to connect the inner end of link 43 with the assembly. The outer end of arm 104 has connected to it the free end of a spring 108, the opposite end of which is secured against movement with respect to the casing. This spring assures that follower 93 will constantly be urged into engagement with the periphery of the selected control cam 94. Addi-

tionally, in lieu of spring 82, a spring 109 may be employed which has its free end connected to link 43. This assures that follower 88 will constantly be urged toward a position at which it engages the periphery of a selected control cam 87.

As will be understood, in connection with a mechanism of the type shown in FIG. 5, a turning of shaft 83 will serve to lift a selected cam 87 to a position where it cooperates with the follower 88. Therefore, as the mechanism operates, that follower will be rocked to correspondingly move the inner end of link 43 in the manner heretofore described, and thus control the lateral movements of the needle bar so that a pattern will be produced by the combined action of the selected pattern cam and eccentric 47. Simultaneously with this operation of the mechanism, follower 93 will be rocked to transmit movements to shaft 67. That shaft, through arm 105, will control the position of the needle by transmitting movements to link 43 through pivot 106 and member 48. Therefore, the resultant pattern will also include factors as controlled by one of the cams 94. The other parts of the machine as heretofore described may all be present, so that a competent operator will be able to produce simple or involved stitch patterns precisely as desired.

Attention is now again invited to FIG. 4 and especially to the detailed operating mechanism controlling the functioning of the stitch-forming apparatus. It will be primarily seen that the mechanism as illustrated in FIG. 5, involving the needle or bight control and the position controls, has been illustrated. For this purpose, the same reference numerals as designated the parts in FIG. 5 have been employed in connection with corresponding parts in FIG. 4. In addition, there is shown in FIG. 5 in the assembly a further group of control cams. These serve to govern the operation of the feed dog 26. Accordingly, the latter may, under this control, produce long stitches or short stitches, together with stitches of intermediate lengths. Also, it may serve to feed the material being worked on in either a forward or reverse direction.

Thus, in FIG. 4 a third group of lifting selector cams 107 is carried by shaft 83. These cams or elements cooperate with arms corresponding to arms 56, 86 and 95 in order to selectively raise one of those arms and the cam 110 carried thereby. A follower 111, preferably in the form of a bar, overlies the cams 110 of the third group. As in the prior structure, the follower and cams are secured against axial movements with respect to each other, and the cams are driven by a pinion shaft 63 or its equivalent, that shaft being common to all three groups of cams and maintaining the timed relationship of all groups as well as the cams individual to each group. Follower 111 is supported by arms, one of which, as at 112, is in the form of a bell crank. These arms are rockable around the axis of a supporting shaft 113. The second arm of bell crank 112 is pivotally connected to one end of a link 114. The opposite end of that link is also pivotally connected to an arm 115 carried by a shaft 116 rotatably mounted with respect to and preferably extending transversely of the machine housing, as shown. Shaft 116 also carries an arm 117, which by means of a rod or link 118 is connected to the stitch length and reverse control lever 40. The parts are normally maintained in a predetermined position where a forward feed of the material being worked upon results in a predetermined stitch length being achieved.

As will be understood, with a cam 110 of the third group having been selected and raised to elevated position by the proper element 107, shaft 63 will cause the periphery of that cam to traverse follower 111, thereby swinging the latter and rocking bell crank 112, link 114, shaft 116 and arm 117. Follower 111 will be maintained in operative association with the selected control cam by the tension exerted through spring 119 acting back through the linkage through bell crank 112. In any event, as rod or link 118 is reciprocated through

this cooperation of parts, control 40 will be shifted. Initial shifting will result in the length of the stitches produced being diminished, in that feed dog 26 will feed the material at a lesser rate of speed. By moving the parts to a further position, feed dog 26 may become inoperative to shift the material, incident to the movement occurring on the part of pitman 33. If control portion 40 is moved beyond this position, then a reverse feed of the material will occur.

It is preferred that the ratio of drive between gears 45 and 46 be such that for each two revolutions of shaft 14, eccentric 47 will make one revolution. The ratio of drive between worm 63 and worm gear 66 will depend upon the contouring of the several cams which are driven by the pinion shaft. On the pattern dial 42 shown in FIG. 4, various stitches have been illustrated. By way of example, the one shown at A is achieved solely by the cams of group 96. The pattern at B follows as a consequence of the response of the mechanism to selected cams of groups 87 and 94. The pattern under C results from the control exercised by individual cams of groups 87. Again, the pattern under D is caused by the action of the individual cams in groups 87 and 94, similarly to the pattern under B. The stitch pattern indicated at E results from the combined response of selected cams of groups 94 and 110. A stitch of the type indicated at F is achieved by control of the mechanism by individual cams of groups 87, 94 and 110. The G type stitch results solely from the operation of a cam of the 87 group, and a stitch as at H is produced by the operation of a cam of the same group. The dial will also preferably as shown include a suitable symbol or legend, which, if adjusted to proper position by rotation of the dial, will result in no cam of any of the three groups being lifted to a position at which it cooperates with its follower. Of course, under all foregoing conditions the eccentric 47 will produce the basic reciprocation of link 43. Also under all these conditions, knob 41 may be adjusted to further modify the characteristics of the resultant stitch.

Thus, among others, the several objects of the invention as specifically aforementioned are achieved. Obviously, numerous changes in construction and rearrangements of the parts may be resorted to without departing from the spirit of the invention as defined by the claims.

I claim:

1. A sewing machine to produce ornamental stitches including in combination a frame, a rotatable drive shaft mounted thereby, a needle bar, means for supporting the bar for both lateral and reciprocating movements with respect to said frame, means for connecting said bar with said drive shaft to reciprocate as said shaft rotates, movable means connected to said supporting means for effecting lateral movements of the latter and bar, an operating assembly comprising a plurality of selector cams, a manually rotatable shaft mounting the same and supported by said frame, arms mounted by said frame to be engaged by said cams and rocked thereby, apertured pattern cams rotatably supported one by each of said arms, ring gears defining the edges of such apertures, a pinion shaft connected to be rotated by said drive shaft and extending through the apertures of said pattern cams in engagement with the gears to thereby rotate such pattern cams, a single elongated and movable follower disposed adjacent said pattern cams and moved by the latter as an arm mounting a pattern cam is rocked to shift that cam into operating engagement with said follower and a connecting structure between and transmitting movements of the follower to the supporting means of the needle bar to impart to the latter lateral movements.

2. In a sewing machine as defined in claim 1, a mechanism forming a part thereof for displacing the stitching zone of the bar to one and the other side of a given point, a second operating assembly as defined in claim 1 forming a part of said machine and a second con-

necting structure between the follower of the latter assembly and said needle bar for displacing the latter to either side of such point.

3. In a sewing machine as defined in claim 2, a mechanism for feeding material to be stitched past said needle bar, means forming a part of said mechanism for varying the amount of such feed and the direction thereof, a third assembly also forming a part of said machine and corresponding to the assembly as defined in claim 1 and a connecting structure between the follower of that third assembly and the feeding mechanism for operating the latter.

4. In a sewing machine as defined in claim 2, a shaft common to both assemblies and said shaft mounting the selector cams of both such assemblies.

5. In a sewing machine as defined in claim 3, a pinion shaft common to all said assemblies and engaging the ring gears forming a part of the pattern cams thereof.

6. A sewing machine to produce ornamental stitches including in combination a needle bar, means for supporting the same for reciprocating and lateral movements, drive means operatively connected to such bar for causing reciprocation of the latter, a rotatable cam shaft, means operatively connecting said shaft to be rotated by said drive means, a plurality of cams supported to rotate with said shaft, a single follower common to said cams and extending parallel to said cam shaft, means securing said cams and follower against axial movement one with respect to the other, means connecting said follower with said needle bar to cause lateral movements of the latter in response to movements of said follower, and manually controlled means for selectively disposing said cams and follower in positions at which an elected one of said cams causes movements of said follower, said manually controlled means including a further rotatable shaft, rockingly mounted arms to cause movements of a cam and follower such that they shift relative to each other to cause the surface of the cam to operatively engage the follower, means carried by said further shaft and connected with said arms for causing such shifting, said arms being connected one to each of said cams, the latter being each formed with an opening of a diameter greater than that of said cam shaft and said cam shaft extending through and drivingly contacting the edges of said openings to cause rotation of said cams.

7. In a sewing machine as defined in claim 6, said cam shaft being formed with axially extending teeth and each opening of said cams being formed with a series of inwardly extending interengaging teeth defining the edges of the openings.

8. In a sewing machine to produce ornamental stitches, in combination, a movably mounted needle bar, means for reciprocating said bar, a link connected to said bar for moving the same laterally, a plurality of cams, axially disposed with respect to each other, means for rotating said cams, supporting means to prevent axial movements of said cams, means operatively connected to said cams and bar reciprocating means for rotating said cams in timed relationship to the reciprocations of said bar, a single follower extending across said cams, means supporting said follower solely for movements toward and away from the cams, selective engaging means connecting said follower solely with one of said cams, said selective engaging means comprising a manually rotatable shaft, selector cams secured to said shaft, rockingly mounted arms each rotatably supporting one of said first named cams, and follower portions forming parts of said arms to be engaged by said selector cams and thus rock an arm to move its supported cam into cooperating engagement with said follower.

9. In a sewing machine to produce ornamental stitches, in combination, a movably mounted needle bar, means for reciprocating said bar, a link connected to said bar for moving the same laterally, a plurality of cams, axially disposed with respect to each other, means for rotating said cams, supporting means to prevent axial movements

of said cams, means operatively connected to said cams and bar reciprocating means for rotating said cams in timed relationship to the reciprocations of said bar, a single follower extending across said cams, means supporting said follower solely for movements toward and away from the cams, means connecting said follower solely with one of said cams, the means for rotating said cams comprising a rotatable pinion shaft operatively connected for movement with said bar as it reciprocates, said cams being formed with openings of a diameter larger than that of said pinion shaft and gear teeth extending inwardly from said openings and engaged by the teeth of said pinion shaft.
